CYLINDER CONSTRUCTION FOR RECIPROCATING ENGINES

Filed Oct. 14, 1931

UNITED STATES PATENT OFFICE

1,928,411

CYLINDER CONSTRUCTION FOR
RECIPROCATING ENGINES

Milton O. Cross, Detroit, Mich.

Application October 14, 1931. Serial No. 568,791

7 Claims. (Cl. 123—173)

This invention relates to cylinder constructions for reciprocating engines and the object of the invention is to provide a metal cylinder sleeve which may be mounted in an engine block 5 of lighter metal and which is provided with integral seats for the inlet and exhaust valves.

Another object of the invention is to provide a cylinder construction by which a hard wearing surface is provided for the engine piston and 10 a hard metal surface is also provided for the valve seats which are formed integrally with the cylinder and allowing the remainder of the engine to be built of aluminum or other light metal to provide an exceptionally light weight engine.

15 A further object of the invention is to provide a tubular cylinder member having a relatively thick flange at the upper end which is apertured and faced to provide seats for the engine valves, the said flange being secured in position between the engine block and cylinder head.

20 Another object of the invention is to provide a cylinder having a flange at the upper end, in which the cylinder and flange are cast in one piece and the flange is provided with ports faced off to provide seats for the valves of the engine.

25 These objects and the several novel features of the invention are hereinafter more fully described and claimed and the preferred form of construction by which these objects are attained 30 is shown in the accompanying drawing in which—

Fig. 1 is a section through an engine embodying my invention and showing the valves arranged side by side at one side of the cylinder.

Fig. 2 is a section through another type of engine in which the valves are arranged one behind the other at one side of the cylinder.

The cylinder 1, shown in Fig. 1, is tubular in 35 form and is provided with a relatively thick flange 2 about the upper end. The cylinder 1 and flange 2 are cast integrally and the cylinder is machined on the inside to receive the piston 3 and is machined on the outside to fit within the cylindrical aperture provided therefor in the engine block 4. The flange 2 is provided with a 40 pair of ports 5 arranged side by side at one side of the cylinder and only one of these ports is shown in Fig. 1. The flange 2 is faced off at 45 to provide a seat for the valve 7 which is of the usual type. The flange 2 fits on the top 50 of the engine block 4 and the cylinder head 8 is positioned on top of the flange 2 and is secured to the engine block by means of the usual cylinder head bolts 9. The compression chamber 10 in the cylinder head extends over the flange 2 and cylinder 1 and over the valve 7, as shown

in Fig. 1, and a spark-plug 11 is secured in the cylinder with the sparking points extending into the compression chamber 10. The cylinder 1 and flange 2 may be made from cast-iron, steel, bronze or other suitable metal which will stand 60 comparatively hard wear, while the cylinder head 8 and engine block 4 may be formed of aluminum or other light metal to provide a light weight motor.

An alternative form of the construction is 65 shown in Fig. 2 in which the cylinder 1 and flange 2 are formed integrally but the ports 12 through the flange 2 are arranged radially in relation to the cylinder; that is, one valve is positioned behind the other. This flange 2 is faced off at 6 70 to provide seats for the valves 13 and the combustion chamber 14 extends over these valves and is provided with an aperture 15 for the spark-plug. In either form, gaskets 16 are provided between the flange 2 and the engine block and gaskets 17 75 are provided between the flange 2 and the cylinder head 8 or 18 as the case may be. This arrangement provides hard metal surfaces for the valve seats and cylinder walls and at the same time allows the use of lighter and softer metals 80 for the crank case, engine block and cylinder head.

From the foregoing description it becomes evident that the device is very simple and efficient in operation, will not easily get out of order, provides 85 hard metal surfaces at the points of greatest wear and provides a device which accomplishes the objects described.

Having thus fully described my invention, its 90 utility and mode of operation, what I claim and desire to secure by Letters Patent of the United States is—

1. In a cylinder construction for reciprocating engines, an engine block having a series of cylindrical apertures, a cylindrical sleeve fitting in 95 each cylindrical aperture and having an integral flange about the upper end thereof, the flange resting on the upper end of the cylinder block and being provided with valve ports therethrough, each valve port being faced off to provide a valve 100 seat, a valve seating on each valve seat and a cylinder head positioned on the said flange and secured to the engine block to bindingly secure the said flange between the cylinder head and engine block. 105

2. In a cylinder construction for reciprocating engines, an engine block having a series of cylindrical apertures, a cylindrical sleeve fitting in 110 each cylindrical aperture and having an integral flange at the upper end, the flange being pro-

vided with inlet and exhaust ports and being faced off to provide valve seats about the said ports, a gasket on each side of the said flange, a cylinder head and means for bindingly securing 5 the said flange and gaskets between the cylinder head and engine block.

3. In a cylinder construction for reciprocating engines, an engine block formed of light weight metal and having a series of cylindrical apertures, a cylindrical metal sleeve fitting each cylindrical aperture, a flange formed integrally with the upper ends of the cylindrical sleeves, the flange being provided with inlet and exhaust ports and being faced off to provide valve seats 10 about the said ports, and a cylinder head positioned on said flange and secured to the engine block.

4. In a cylinder construction for reciprocating engines, an engine block having a series of cylindrical apertures, a cylindrical sleeve fitting in each cylindrical aperture and having an integral flange at the upper end thereof, the flange being provided with valve ports therethrough and being faced off to provide valve seats about the ports, 20 a cylinder head and means for bindingly securing the said flange between the cylinder head and engine block.

5. In a cylinder construction for reciprocating engines, an engine block having a cylindrical aperture, a cylindrical sleeve fitting in the said aperture and having an integral flange at the upper end, the flange being provided with inlet and exhaust ports and being faced off to provide valve seats about the said ports, a cylinder 30 head provided with a combustion chamber over

the cylindrical sleeve and ports and means for bindingly securing the flange between the cylinder head and engine block.

6. In a cylinder construction for reciprocating engines, an engine block having a cylindrical aperture, a cylinder lining adapted to be inserted into and fitting within the cylindrical aperture and having an integral flange at the upper end thereof overlying the cylinder end and through which the cylinder opens, a series of ports in the said flange and the flange being provided with faces at the said ports forming valve seats, a cylinder head mounted on the flange and secured to the block to prevent displacement of the lining. 80

7. In cylinder construction for reciprocating engines, an engine block formed of a material unadapted to provide bearing surfaces for pistons or valves of an engine, and providing a cylinder and valve openings, a cylindrical lining formed of a high grade metal providing good wearing surface for the piston and valves and insertible in the block, the said flange overlying the cylinder end and having ports therein formed with valve seats and registering with the openings in the engine block, valves reciprocatably mounted in 90 the engine block and having a valve member for seating on the valve seats of the said ports of the flange, a piston reciprocatable in the lining, and a cylinder head secured to the end of the engine block engaged by the flange and securing the 100 flange in place, said head providing a compression chamber in communication with the valve ports.
